(57) **CLAIM**

The ornamental design for a dog water fountain, as shown and described.

DESCRIPTION

FIG. 1 is a perspective view of the dog water fountain showing my new design;

FIG. 2 is a perspective view thereof from another angle;

FIG. 3 is a perspective view thereof from another angle;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a cross-sectional front view taken along and in the direction of line 10-10 in FIG. 4.

The broken lines shown in the drawings represent portions of the dog water fountain that form no part of the claimed design.
